SHEET DELIVERING APPARATUS

Albert J. Hory, Detroit, Mich.

Application June 19, 1948, Serial No. 34,080

1 Claim. (Cl. 271—74)

1

The present invention relates to means for handling sheets of paper or the like in feeding such sheets to and removing them from presses, specifically engraving presses.

Among the objects of the invention is to provide a simple, relatively inexpensive, efficient means for lifting a single sheet of paper from a stock pile, placing it in proper position in a press and, after the impression has been made, lifting it from the press and depositing it at a suitable location, and, in the case of engraving presses, turning it face or ink-side up.

Another object is the provision of means of the type indicated which is actuated from a suitable portion of the press mechanism so that it is actuated in exact synchronism with the press.

Other objects will readily occur to those skilled in the art upon reference to the following description and the accompanying drawing in which

Fig. 1 is a perspective view showing the device mounted in position to tend a press, a portion of the latter being shown.

Fig. 2 is a view of the mechanism, from the left of Fig. 1, parts being omitted for clarity.

Fig. 3 is an end view of the complete mechanism.

Fig. 4 is an enlarged elevation of the valve mechanism.

Fig. 5 is a sectional view of the valve.

Fig. 6 is a view in elevation of the paper stock magazine and means for positioning said stock therein.

As indicated in the drawings, the structure comprises broadly mechanism including arms carrying suction cups which pick up a single sheet of paper from a suitably located pile of stock and convey it to its proper location in a press and then release it to receive the impression. It also comprises other arms carrying suction cups which pick up the impressed sheet and carry it to a suitable location where the sheet is released, during which operation the sheet is reversed.

In Fig. 1 a portion of a conventional press is shown at A, this including among other mechanism a suitable rotary element B (Fig. 3) by which the present device is actuated. Located in front of the press A and fixed thereto in any suitable fashion is a table 10 serving as a support for the feed mechanism about to be described.

Referring to Fig. 1, a stock of paper is shown at 11 with single sheet 11A in the press and the sheet handling members in the positions these occupy immediately after the press has made the impression. The feeder fingers 12 are in position to pick up a fresh sheet and the take-off fingers 13 are in position to remove the impressed sheet from the press.

2

In Fig. 2, the fingers are at the other extremes of their motions; that is, the fingers 12 are in the position of delivering a sheet to the press while the fingers 13 are in the position in which they release an impressed sheet.

As shown best in Figs. 2 and 3, the mechanism for causing the desired operation of the fingers 12 and 13 comprises a shaft 20, to an end of which is fixed a crank arm 20A connected to a pitman 20B actuatable from a suitable rotary member B forming part of the press mechanism.

The attachment of pitman 20B to the arm 20A is preferably through a suitable adjustable member 20C and the attachment of arm 20A to shaft 20 is also an adjustable clamp device so that the radial position of the arm on the shaft and the length of stroke of the arm may be accurately adjusted.

Carried on the shaft 20 and adjustably fixed thereto is a second arm 21 which, as shown in full lines in Fig. 3, extends upwardly and then forwardly, being sufficiently long in this forwardly extending portion to reach to a point near the press.

25 This arm 21 at its end is connected to a shaft 22, the latter being rotatable in the end of the arm and carrying the fingers 12. Shaft 22 is fixed at one end to one end of a link 23 and this link, at its other end is hinged to a second link 30 23A which in turn is hinged to the end of a swinging arm 24 hinged, as at 24A to table 10. The position of the hinge 24A and the length of the several links and arm is such that, in the full line position of Fig. 3 the ends of fingers 12 are close to the plunger of the press A.

The shaft 20 also has fixed thereto a bevel gear 30 meshing with a suitable mating gear on a shaft 31 arranged at right angles to shaft 20. This shaft 31 carries an arm 32, similar to arm 21, which is connected at its outer end to a shaft 32A upon which are carried the fingers 13, the shaft 32A being rotatable with respect to the arm.

This shaft 32A is fixed to the end of a link 45 32B, which at its other end is hinged to a swinging arm 32C, in turn hinged as at 33 to the table 10, the link fingers and arm 32C being of such lengths as to allow the fingers to reach the position shown in Fig. 1.

50 It will be noted that the hinge point 33 is shown as a circular member since it is desirable to provide at this point a suitable coil spring to counterbalance the weight of arm 32 and attached parts. Such springs are well known and hence no detailed construction is shown.

The bevel gearing 30 should be so arranged that the arms 21 and 32 move forward and back alternately. The fingers 12 and 13 are tubular and provided at their forward ends with suction

60 cups 12A and 13A and to the rearward end of

each finger is attached a flexible tube 35 leading to a header 36 shown branched and mounted upon a suitable elevated support 36A. From the header 36 a tube 37 leads to a valve 38 shown in detail in Figs. 4 and 5.

This valve consists of a body or housing 38A in which fits a cylindrical member 38B having a diametrical passage 38C to which is connected a branch passage 38D. The valve body is also provided with openings or passages 38E and 38F diametrically opposite each other and to one of which, 38F, is connected the tube 37 leading to header 36. To the other passage 38E is connected a suction pump (not shown).

The valve body is also provided with another passage 38H opening to the atmosphere and so arranged that when the member 38B is partially rotated to bring the branch passage 38D into registry with passage 38F, the other end of passage 38C will register with the opening 38H and thereby relieve suction on the fingers.

The valve member 38B is oscillated from the position shown in Fig. 5 suction position to the position just described by the means shown in Figs. 3 to 4.

As shown in Fig. 3, the shaft 31 carries a large gear 40 meshing with a smaller gear 40A fixed to a short shaft 41. Also fixed to shaft 41 is a gear 40B meshing with a somewhat smaller gear 40C fixed to a shaft 42 mounted for rotation in axial alignment with the valve member 38B. Upon the same shaft 42 is fixed a chuck 43 within which is a cylindrical block 43A held in adjusted radial location by a set screw 43B.

This block 43A carries a pin 44 extending toward the valve 38 and a second pin 44A is mounted in the edge of the chuck 43. These two pins coact with a radially extending pin 45 fixed to the hub 38K of valve member 38B and as the chuck 43 is oscillated, cause the valve member to be moved from its one position to the other, overrun being prevented by the spring pressed ball 46 carried by valve body 38A coacting with suitable notches in the member 38B.

By suitable operation of the valve 38, the suction cups 12A and 13A are simultaneously activated and deactivated.

Since the path of movement of the feed fingers 12 is quite accurately determined and since the depth of the pile of stock is constantly decreasing during the operation of the press and feed means, means is provided to maintain the location of the top sheet in the stock pile. This means is shown in detail in Figs. 2, 3 and 6.

In these figures, the stock magazine is shown as consisting of a slanting base or support 50 carrying a slide 50A, the paper stock being placed on edge on the base 50 and against the slide 50A. To this slide is connected a pair of tapes 50B (shown in Fig. 2, hanging detached) extending substantially parallel to the base 50 over pulleys or rollers 50C, and then downwardly to wrap around a shaft 51 upon which is fixed a pair of ratchet wheels 51A and 52, the former 51A, coacting with a suitable pawl 51B carried by a post 51C fixed to the table 10. This ratchet wheel and pawl combination serves to maintain the shaft 51 against reverse movement.

The positive movement of shaft 51 and consequent forward movement of the slide 50A and stock is caused by the mechanism shown in detail in Figs. 2 and 6.

In these figures, the shaft 20 is shown as having fixed thereto a sprocket 55 driving through

chain 55A a second sprocket 56 upon the hub of which is a projecting radial pin 56A, this second sprocket being loosely mounted on shaft 51. Adjacent this sprocket 56 and also loosely mounted on shaft 51 is a cup-shaped member 57 adapted to cover the ratchet wheel 52, a small portion of the cup being cut away as shown in Fig. 6 at 57A to expose a few of the ratchet teeth.

This member 57 is positioned radially of shaft 51 in accordance with the thickness of the stockpile by means of a pivoted arm 58 one end of which contacts the top of the stockpile through the cross member 58D and the other of which is connected through a link 58A to an arm 58B fixed to the member 57, a spring 58C suitably anchored, being arranged to bias the linkage toward stock contacting position.

Arranged alongside of ratchet wheel 51B is a large gear 60 loosely carried on shaft 51 and meshing with a smaller gear 60A fixed to shaft 20.

The gear 60 carries on one face a pawl 60B located over the ratchet wheel 52 and adapted to coact therewith to produce a positive movement of shaft 51. The pawl 60B, however, is allowed to act on wheel 52 or prevented from doing so by the position of member 57 and, as stated above, this position is determined by the amount of stock in the magazine.

As the stock is used from the top of the pile, the linkage 58 will move the member 57 counterclockwise so that the pawl 60B can drop upon wheel 52 and move it forward. The pawl 60B is released from the wheel by the action of the pin 56A striking another pin 61 carried by member 57.

I claim:

In paper handling means for engraving presses, an oscillatable arm having suspended therefrom at its free end one end of a link, a laterally extending rod fixed to said link, a second oscillatable arm arranged below and hinged to the other end of said link, means for oscillating said second arm, suction cups carried by said rod and in fixed relation thereto, said arms and link being so arranged that, at one end of the oscillation of the second arm, the first arm and link are in extended relation and at the other end of said oscillation the link is approximately parallel to and below the first arm, and means for producing a partial vacuum in said cups during said extended relation and for breaking said vacuum at the other end of said oscillation.

ALBERT J. HORY.
